SULPHUR VAT WALL FORM

Lyle D. Gilmore, Worland, Wyo., assignor to Texas Gulf Sulphur Company, New York, N.Y., a corporation of Texas

Filed May 28, 1957, Ser. No. 662,179

5 Claims. (Cl. 18—39)

This invention relates to storage vats for molten sulphur and more particularly to new and novel sideboard sections for use in fabricating the vat retaining walls.

In the mining of subterranean sulphur by the well known Frasch process, hot water is forced below ground into the sulphur deposit to melt the sulphur, and then compressed air is used to force the molten sulphur to the surface where it is poured into huge storage vats for cooling and solidification. The vats are essentially large bins, in some cases made with sheet metal sides, or the sulphur itself is used to make the vat wall by initially pouring molten sulphur into forms placed around the periphery of the vat and on cooling the sulphur hardens to form a wall around the edge of the vat which confines the other sulphur subsequently pumped into the vat. Usually the practice has been to form the sulphur vat by building the confining wall, whether of sulphur itself as described above, or other material, step-wise, i.e. building the confining wall to an initial height considerably less than the desired ultimate sulphur vat level, and after the molten sulphur has been filled to that height, then raising the wall, or in the case of the sulphur wall, constructing the next higher level.

Although the above described methods used heretofore have been generally satisfactory, certain inherent faults have been encountered. When using the sulphur wall technique, portions of the wall sometimes break away from the main body of the vat and create falling hazards. Furthermore, the sulphur of the thin wall cools more rapidly than that in the main body of the vat and it is generally hard and rather difficult to crush when it is desired to break down the sulphur vat into smaller pieces for use or shipping. With the other vat wall types, no means of construction was available which afforded the desired simplicity and efficiency.

It is an object of this invention to provide a sideboard or wall panel member for use in constructing a sulphur vat form which utilizes the hardened sulphur itself to provide anchoring means for raising the wall to a higher level for the reception of the next successive layer of sulphur in the vat.

Another object of the invention is to provide such a sideboard which does not require any separate connecting means or fittings in fabricating the vat wall.

Another object is to provide a sideboard which does not require the use of tools in either constructing or dismantling the vat wall.

Briefly, this invention involves a vat form for the step-wise casting of molten sulphur consisting of a plurality of sideboard elements each adapted for mating with adjacent elements at its ends and having a vertical dimension less than the desired element sulphur vat level. Each of such elements is comprised of a wall member having at least one pair of vertically spaced laterally projecting pins disposed in a parallel relationship to one another on one side of the wall member. Each of the pins is preferably tapered toward its free end and is affixed to the wall member on its other end at a downward acute

2

angle of, for example, sixty degrees. This structural configuration thus provides a form which can be successfully stepped up by the insertion of the bottom pins into the holes made into the cast sulphur by the top pins, and by virtue of the downwardly depending pins, the sideboard is held substantially rigidly in place to provide a confining wall for the introduction of additional molten sulphur into the vat.

Other objects and features of the invention will become apparent in reading the following description and claims, and in the drawings in which:

Fig. 1 is an isometric view of three sideboard members in relative position for formation of a vat wall portion;

15 Fig. 2 is a profile view of one sideboard member;

Fig. 3 is a partially sectioned profile view of a sideboard member in place against a sulphur vat; and

20 Fig. 4 is a partially sectioned profile view of a sideboard member shown raised to contain the next higher successive layer of sulphur.

25 Referring now to the drawings, Fig. 1 shows one structural embodiment of the invention. Each vat form section or sideboard 10 consists of a wall member 11 and has a pair of vertical handle members 12 affixed to the outer side 13 thereof at spaced positions from one another. On the other side 14 of wall member 11 are two pairs of laterally projecting pins 15. The pins of each pair are vertically spaced from one another and are parallel to one another. They are preferably tapered toward their respective free ends 16 and are also preferably affixed to the wall member at a downward acute angle, e.g. 60 degrees. Each pair is spaced from the other as shown, thus each wall member 11 has two upper pins 17 adjacent the top edge 18 thereof, and two bottom pins 19 adjacent the bottom edge 20. For best results it is preferred that the free ends 16 of the two bottom pins 19 lie above a horizontal plane through the bottom edge 20 of the wall member 11 so that the sideboard 10 will stand upright, using the bottom pins 19 as supporting members as shown in Fig. 2.

30 The entire assembly can be made of any suitable material, but in its preferred form it has been found that aluminum gives a good combination of lightness and strength. The handles 12 as well as the pins 15 can 35 likewise be constructed of aluminum and affixed to the wall member 11 by welding or other suitable means. Any convenient type of handle means can be employed, or even dispensed with. The pins 15 may be entirely cylindrical, without taper, and may be affixed to the 40 wall member 11 at right angles rather than at an acute angle, however, the form described above has been found to be highly desirable and superior in many respects. Furthermore, depending on the dimensions of the sideboard 10 and possibly other factors it may be desirable 45 to use only one pair of pins, or several pairs, the choice 50 being governed by the particular situation.

46 The sideboard elements 10 are adapted as shown for 55 mating with adjacent elements at its ends 21 as positioned for the construction of the vat form. Corner elements 60 22 are provided with right angled flange portions 23 to provide strength for the vat form at the corners.

56 In use the sideboard elements 10 are assembled in the 65 general fashion shown in Fig. 1. Starting from the bottom of the vat before any molten sulphur is poured therein, the side boards 10 are mated by lap joints at their ends 21 with those of adjacent sideboards 10. All 70 are maintained in an upright position on the vat floor 24 by their respective bottom pins 19. After a vat form of the desired shape and dimension is thereby constructed, molten sulphur 25 is poured into the confined space to a level at or near the top edge 18 of the sideboard elements 10, as shown in Fig. 3. After the sul-

phur 25 has cooled and hardened the sideboard elements 10 are pulled away from the cake leaving tapered channels 26 conforming to the precise dimensions of the pins 15. The sideboards 10 can then be raised and positioned against the solidified cake so that the bottom pins 19 fit into the channels 26 previously occupied by their respective top pins 17, thus forming a raised vat form around the periphery of the cake and affording additional space for the reception of more molten sulphur (see Fig. 4). In this fashion any number of successive layers can be formed in this step-wise fashion.

Thus it can be seen that the present invention provides a simple and efficient means for constructing a sulphur vat form without the need for separate connecting means or the use of tools or other equipment. The objections to the prior wall structures have been eliminated and the cost savings effected by the present invention should be advantageous.

While one embodiment of this invention has been shown and described, it is to be understood that certain changes can be made by those skilled in the art without departing from the scope and spirit of this invention.

I claim:

1. A sideboard for a sulphur vat form comprising a unitary combination of molding wall, recessed form pin and anchor pin comprising a wall member oriented in a vertical plane having a pair of substantially identical vertically spaced and aligned laterally projecting pins fixed on the inner face thereof in a parallel relationship to one another, said pins tapered toward their free ends and downwardly oriented with respect to said side, the upper pin of said pair comprising a form pin adapted to project into sulphur poured in and confined by said form to create in said sulphur when it hardens a socket adapted to receive said bottom pin of said pair which comprises an anchor pin adapted to support said form above the surface of a layer of solidified sulphur which had been poured and set in said form to provide a mold for another layer of sulphur to be cast on the solidified layer.

2. A sideboard for a sulphur vat form comprising a unitary combination of molding wall, recessed form pin and anchor pin comprising a wall member oriented in a vertical plane having a pair of substantially identical vertically spaced and aligned laterally projecting pins fixed thereto and disposed in a parallel relationship to one another adjacent the respective top and bottom edges of said member on the inner face thereof, said pins tapered toward their free ends and downwardly oriented at an angle of about sixty degree to said side, the upper pin of said pair comprising a form pin adapted to project into sulphur poured in and confined by said form to create in said sulphur when it hardens a socket adapted to receive said bottom pin of said pair which comprises an anchor pin adapted to support said form above the surface of a layer of solidified sulphur which had been poured and set in said form to provide a mold for another layer of sulphur to be cast on the solidified layer.

3. A sideboard for a sulphur vat form comprising

10

a unitary combination of molding wall, recessed form pin and anchor pin comprising a wall member oriented in a vertical plane having a pair of substantially identical vertically spaced and aligned laterally projecting pins fixed thereto and disposed in a parallel relationship to one another adjacent the respective top and bottom edges of said member on the inner face thereof, said pins tapered toward their free ends and downwardly oriented at an angle of about sixty degree to said side, the free end of the lower pin lying above the horizontal plane of the bottom edge of said member, the upper pin of said pair comprising a form pin adapted to project into sulphur poured in and confined by said form to create in said sulphur when it hardens a socket adapted to receive said bottom pin of said pair which comprises an anchor pin adapted to support said form above the surface of a layer of solidified sulphur which had been poured and set in said form to provide a mold for another layer of sulphur to be cast on the solidified layer.

20

4. A vat form for the step-wise casting of molten sulphur consisting of a plurality of sideboard elements oriented in a vertical plane each consisting of a unitary combination of molding wall recessed form pin and anchor pin and adapted for mating with adjacent elements at its ends and being comprised of a wall member having a pair of substantially identical vertically spaced laterally projecting pins fixed thereto and disposed in a parallel and vertically aligned relationship to one another adjacent the respective top and bottom edges of said member on the inner face thereof, said pins tapered toward their free ends and downwardly oriented at an angle of about sixty degrees to said side.

25

5. A vat form for the step-wise casting of molten sulphur consisting of a plurality of sideboard elements oriented in a vertical plane each consisting of a unitary combination of molding wall recessed form pin and anchor pin and adapted for mating with adjacent elements at its ends and having a vertical dimension less than the desired ultimate sulphur vat level, each of said

30

elements is comprised of a wall member having a pair of vertically spaced laterally projecting pins fixed thereto and disposed in a parallel relationship to one another adjacent the respective top and bottom edges of said member on one side thereof, said pins tapered toward their free ends and downwardly oriented at an angle of about sixty degrees to said side whereby said form during use can be successively stepped up by the insertion of the bottom pins into the holes made in the cast sulphur by the respective top pins of the pairs to provide additional casting height for the vat.
